FIG. 1 is a front, top, left side perspective view of the exhaust gas aftertreatment system showing our new design; FIG. 2 is a rear, top, right side perspective view of the exhaust gas aftertreatment system; FIG. 3 is a front view of the exhaust gas aftertreatment system;

FIG. 4 is a rear view of the exhaust gas aftertreatment system;

FIG. 5 is a left side view of the exhaust gas aftertreatment system;

FIG. 6 is a right side view of the exhaust gas aftertreatment system;

FIG. 7 is a top view of the exhaust gas aftertreatment system; and,

FIG. 8 is a bottom view of the exhaust gas aftertreatment system.

The broken lines depict portions of the exhaust gas aftertreatment system that form no part of the claimed design.

1 Claim, 7 Drawing Sheets
